CLAIM

The ornamental design for a lite panel, as shown and described.

DESCRIPTION

FIG. 1 is a front elevational view of a first embodiment of my design;

FIG. 2 is a cross-sectional view taken along the line 2-2 of FIG. 1;

FIG. 3 is a cross-sectional view taken along the line 3-3 of FIG. 1;

FIG. 3A is an enlarged view of a detail of FIG. 3;

FIG. 4 is a front elevational view of a second embodiment of my design;

FIG. 5 is a cross-sectional view taken along the line 5-5 of FIG. 4;

FIG. 6 is a cross-sectional view taken along the line 6-6 of FIG. 4;

FIG. 6A is an enlarged view of a detail of FIG. 6;

FIG. 7 is a front elevational view of a third embodiment of my design;

FIG. 8 is a cross-sectional view taken along the line 8-8 of FIG. 7;

FIG. 9 is a cross-sectional view taken along the line 9-9 of FIG. 7;

FIG. 9A is an enlarged view of a detail of FIG. 9;

FIG. 10 is a front elevational view of a fourth embodiment of my design;

FIG. 11 is a cross-sectional view taken along the line 11-11 of FIG. 10;

FIG. 12 is a cross-sectional view taken along the line 12-12 of FIG. 10;

FIG. 12A is an enlarged view of a detail of FIG. 12;

FIG. 13 is a front elevational view of a fifth embodiment of my design;

FIG. 14 is a cross-sectional view taken along the line 14-14 of FIG. 13;

FIG. 15 is a cross-sectional view taken along the line 15-15 of FIG. 13;

FIG. 15A is an enlarged view of a detail of FIG. 15;

FIG. 16 is a front elevational view of a sixth embodiment of my design;

(Continued)

FIG. 17 is a cross-sectional view taken along the line 17-17 of FIG. 16;
 FIG. 18 is a cross-sectional view taken along the line 18-18 of FIG. 16;
 FIG. 18A is an enlarged view of a detail of FIG. 18;
 FIG. 19 is a front elevational view of a seventh embodiment of my design;
 FIG. 20 is a cross-sectional view taken along the line 20-20 of FIG. 19;
 FIG. 21 is a cross-sectional view taken along the line 21-21 of FIG. 19;
 FIG. 21A is an enlarged view of a detail of FIG. 21;
 FIG. 22 is a front elevational view of a eighth embodiment of my design;
 FIG. 23 is a cross-sectional view taken along the line 23-23 of FIG. 22;
 FIG. 24 is a cross-sectional view taken along the line 24-24 of FIG. 22; and,
 FIG. 24A is an enlarged view of a detail of FIG. 24.
